DESIGN FOR A HAT RACK

Fred Jacobius, New York, N. Y.

Application April 22, 1939, Serial No. 84,507

Term of patent 3½ years

To all whom it may concern:

Be it known that I, Fred Jacobius, a citizen of the United States of America, residing in New York city, in the Borough of Manhattan, county and State of New York, have invented a new, original, and ornamental Design for a Hat Rack, of which the following is a specification, reference being had to the accompanying drawings, forming part thereof, wherein

Figure 1 is a perspective view of a hat rack showing my new design.

Figure 2 is a top plan view of the hat rack shown in Figure 1.

Figure 3 is a bottom plan view thereof.

Figure 4 is an elevational view of the sections comprising the hat rack shown in Figure 1.

I claim:

The ornamental design for a hat rack, substantially as shown,

FRED JACOBIUS,
